UNITED STATES PATENT OFFICE

CARL A. RUNDQUIST, OF CHICAGO, ILLINOIS

COFFEE URN BAG

Application filed April 4, 1932. Serial No. 603,012.

My invention has to do particularly with filter bags for coffee urns, such as are employed by hotels, clubs, restaurants, and coffee shops in the making of coffee.

5 As is well known these filter bags are of considerable size, and they are clamped within the open top of the urn usually by means of a spring wire threaded through a hem on the upper edge of the bag about the opening.

10 These bags, not being permanent in character but usually discarded after being used a few times, are a considerable item of expense; and the bag units must be inexpensive and yet properly shaped to present a substantial circular mouth when distended with a minimum of flutings, tucks and other irregularities difficult of cleansing.

These bags are ordinarily made by sewing together two of the diagonal edges of triangular shaped pieces of filter cloth and the upper edge about the open mouth turned over on the inside to form a reinforcing hem which also receives the clamping ring. Such construction is objectionable in that the mouth of the bag when distended is not truly circular and at the seams is of greater depth, leaving an interior that is not symmetrical.

25 Even if, as is sometimes done, the triangular pieces of material have the upper edges trimmed along an arcuate line in order to make a truly circular distended mouth, the inturned portion of the hem being of greater extent presents, when stitched, gathers or flutings which are not sanitary.

30 In either instance the line of pull in one portion is straight with the threads of the material and in other portions the pull is on the bias, resulting in distortion; and while in the first example the hem may extend uniformly relative to the weave, in the second instance the hem itself extends in non-uniform bias relation to the fabric threads.

35 By my invention the fabric is cut in triangular shape and sewed together along two sides. The upper edge defining the opening is cut along an arcuate line to present a truly circular mouth when distended. However, as the curved edge extends non-uniformly relative to the warp and weft threads of the material, the edge is not turned over but a

separate ring-receiving band is provided, the threads of which extend longitudinally and transversely throughout the length. The edges of the band are reversely folded inwardly to embrace the raw edge of the bag and are stitched thereto, or they may be not only inturned to embrace the bag edge but the edges of the bag and of the band may be interlocked by a felled seam, or such other form of seam connection may be employed as will securely unite them without puckering or fluting.

45 Thus, while the threads of the bag in some portions bear a bias relation to the band, the band uniformly resists downward pull thereon and the connection between the band and the bag proper is so secured and their relation such that but a minimum of distortion of the bag can occur. There are no inequalities of the hem providing pockets for the collection of sediment and the whole is easily cleansed and sanitary. The bag is inexpensive and much more satisfactory than filter bags as hitherto made.

50 In order more clearly to bring out the features characterizing the invention, a preferred embodiment of the same is set forth in the accompanying drawing by way of example.

55 In the drawing,

Fig. 1 is a front elevation of the bag after stitching but in flat condition, the line of fold corresponding to that of the seam at the edge;

Fig. 2 is a similar view at right angles to Fig. 1;

Fig. 3 is a fragmentary enlarged view illustrating the relation between the threads of the band and the body portion;

Fig. 4 is a section on the line 4-4 of Fig. 1 illustrating one form of connection between the band and bag proper; and

Fig. 5 is a modified form of connection between band and bag.

By reference to the drawing it will be observed that in the flat while the warp and weft threads 11 and 12 of the material forming the body 13 extend respectively in a vertical and horizontal direction, the relationship between the threads of the body portion

and that of the band 14 progressively varies from parallelism at 15 midway between the two lines of stitching 16 to a bias relationship at 17 adjacent the two lines of stitching.

8 This condition necessarily results from the generally triangular shape of the pieces from which the body portion is made and it being stitched together along oblique lines 16.

If the upper open edge be reinforced by a 10 seam integral with the body portion, such seam will likewise have the threads extending longitudinally of such seam in certain portions of its length and in other portions diagonally thereof, and as a consequence this 15 supporting hem will be of unequal resistance throughout to vertical pull, permitting the bag to lose its shape disadvantageously; and if, on the other hand, the joined pieces of material forming the bag body are cut along the 20 free edges in a straight line in order that the threads of the hem may extend uniformly relative to its length, in that event the folding over of the material to form the hem will necessarily cause gathers on the inside of the 25 bag which would be unsanitary; and, moreover, the bag will not be symmetrical, the walls along the stitched edges being of greater extent than at a point intermediate the same.

30 By my invention these objections are obviated to the greatest practicable extent in that the reinforcing band 14 is entirely separate and apart from the body material 13 until it is turned and stitched thereto. As the warp 35 threads 18 of the band extend longitudinally of the band and the weft threads 19 extend transversely of the band throughout, eliminating bias relationship, the band uniformly presents resistance to distortion and the material of the bag, even in its bias portions, is 40 securely held against distortion and will give uniform filtering action throughout.

The band may be attached to the bag material in different ways, but I have found the 45 form of seam shown in Fig. 4 to be admirably adapted to the purpose. Therein the band 14 is folded medially of its width with its edges 14a inturned upon themselves to embrace the upper edge 13a of the bag material 50 and is then stitched through as indicated at 20.

A clamping wire 21 is threaded through the loop made by the folded band 14 and serves to clamp and support the same within 55 the mouth of the urn, as is usual practice.

In Fig. 5 another form of seam is shown wherein the band is folded in the precise manner as set forth in Fig. 4 but the raw edge 13a of the bag material is itself folded 60 around one of the edges 14a and stitched through at 20 whereby a secure felled seam is produced.

I claim:

1. A filter bag for urns comprising a body 65 portion of generally conical shape and hav-

ing a substantially circular open mouth, and a supporting band extending circumferentially of the mouth and stitched to the fabric of the bag, said band adapted to be engaged by a clamping ring for supporting the bag in 70 the urn, the threads in the band extending longitudinally and transversely of the band and the threads of the bag extending in some portions parallel to the threads of the band with a gradual divergence therefrom in other 75 portions towards a bias relationship.

2. A filter bag for urns comprising a body portion of generally conical shape and having a substantially circular open mouth, and a supporting band extending circumferentially of the mouth and stitched to the fabric of the bag, said band adapted to be engaged by a clamping ring for supporting the bag in 80 the urn, the warp threads in the band extending longitudinally of the band, and the warp threads of the bag extending in some portions normal to the warp threads of the band with a gradual divergence therefrom in other 85 portions towards a bias relationship.

3. A filter bag for urns comprising a body portion of generally inverted conical shape and having a substantially circular open mouth, and a separate supporting band extending circumferentially of the mouth with its edges reversely turned upon themselves to 90 embrace and stitched to the fabric of the bag, said band adapted to receive internally a clamping ring for supporting the bag in the urn, the warp and weft threads in the band extending longitudinally and transversely of the band and the warp and weft threads of the bag extending in some portions normal 100 and parallel to the corresponding threads of the band with a gradual divergence therefrom in other portions towards a bias relationship. 105

4. A filter bag for urns comprising generally triangular pieces of fabric stitched together along two sides to form a body portion of generally conical shape when distended and presenting a substantially circular open mouth, a band of material in which the warp and weft threads extend longitudinally and transversely of its length, said band folded medially of its width 110 and having its marginal edges inturned upon themselves to embrace and stitched to the raw marginal edge of the body portion, the band adapted to receive internally a distending and clamping ring for supporting 115 the bag in the urn.

5. A filter bag for urns comprising generally triangular pieces of fabric stitched together along two sides to form a body portion of generally conical shape when distended and presenting a substantially circular open mouth, a band of material in which the warp and weft threads extend longitudinally and transversely of its length, said band folded medially of its width and 120 125 130

having its marginal edges stitched to the raw marginal edge of the body portion, the band adapted to receive internally a distending and clamping ring for supporting
5 the bag in the urn.

In testimony whereof I have hereunto subscribed my name.

CARL A. RUNDQUIST.
